UNITED STATES PATENT OFFICE.

JAMES NEIL, JR., OF NEW YORK, N. Y.

GUARD FOR DENTAL INSTRUMENTS.

1,021,065.

Specification of Letters Patent. Patented Mar. 26, 1912.

Application filed March 15, 1911. Serial No. 614,737.

To all whom it may concern:

Be it known that I, JAMES NEIL, Jr., a citizen of the United States, residing at New York, in the county of New York and State of New York, have invented a new and useful Guard for Dental Instruments; and I do hereby declare the following to be a full, clear, and exact description of the invention, such as will enable others skilled in the art 10 to which it appertains to make and use the same.

This invention relates to a new and useful stone guard or shield for dental grinding tools.

15 The invention in its broadest scope aims to provide as its primary object an improved guard of this design, for protecting the tongue and the surrounding tissues of one's mouth against injury.

20 A further object of the invention is to provide the guard with a recess or depression for the reception of a wad of moist cotton or the like for obviating the possibility of the grinding stone becoming hot, and also 25 to improve the cutting and grinding of the stone.

The invention comprises further features and combination of parts, as hereinafter set forth, shown in the drawings, and claimed.

30 In the drawings:—Figure 1 is a view in elevation of a dental grinding tool, showing the application of the improved guard applied thereto, and constructed in accordance with the invention. Fig. 2 is a sectional view 35 through a portion of the guard, showing the grinding tool in elevation, and also illustrating the recess or the cavity for the reception of a moist wad of cotton. Fig. 3 is a detail view of the guard detached from the 40 grinding tool.

Referring to the drawing, 1 designates the hand piece of the dental engine, while 2 denotes the guard shank. The guard shank is tubular in outline, and one end thereof is 45 provided with oppositely arranged L-shaped slots 3, to engage the pins 4 of the hand piece or mandrel, thus constituting a form of slot and bayonet connection between the guard shank and the hand piece or mandrel, so as 50 to hold the guard shank securely in place.

The shank, however, terminates into the guard proper 5, which is in the form of a disk 6, about the periphery of which an annular flange 7 is formed. The disk is provided with a cutaway portion 8 which is segmental in outline, thus providing means to permit the grinding tool to protrude there-through. By this cutaway portion the grinding tool may be inserted between two teeth, in order to grind the surface of one or 60 the other, in order to permit the dentist to treat the desired tooth. The grinding tool or stone is inserted in the mandrel or hand piece subsequently to connecting the guard.

65 The disk of the guard is provided with a recess or concavity 10, for the purpose of receiving a wad of moist cotton or the like. 11. By virtue of the cotton the grinding stone or tool is kept moist, thus preventing to a great extent the stone becoming too hot. 70 The recess 10 is provided with an outward opening 7^a, as clearly shown in Figs. 2, 3 and 4 of the drawings. This opening 7^a is for the purpose of permitting the moist cotton to be inserted in the recess 10 without 75 removing the grinding stone or tool.

From the foregoing, it will be evident that there has been provided a novel form of dental guard for grinding tools or stones, and one which has been found to be simple 80 in construction and efficient in practice. Furthermore, it will be observed that this guard not only provides the above features but also includes novel means for moistening the grinding tool or stone. 85

The invention having been set forth, what is claimed as new and useful is:

1. In combination, a grinding stone, a guard therefor comprising a disk like member having a circumferential annular flange 90 and provided with a segmental cutaway portion, the disk like member having a recess provided with overhanging walls, adapted to contain a wad of moist fiber for moistening the grinding stone, thus preventing the 95 same from becoming too hot, the overhanging walls constituting means to prevent accidental displacement of the moist wad of fiber.

2. In combination with a hand piece of a 10

dental engine, a stone guard detachably connected thereto and provided with a recess having overhanging walls adapted to contain a wad of moist fiber to keep the stone

5 moist so as to prevent the same becoming too hot said recess being provided with an aperture.

In testimony whereof I have signed my name to this specification in the presence of two subscribing witnesses.

JAMES NEIL, JR.
